SIMON B. HESS, OF JAMAICA, NEW YORK.

ELECTRIC SIGNALING SYSTEM.

1,351,422.

Specification of Letters Patent. Patented Aug. 31, 1920.

Application filed September 19, 1916. Serial No. 121,036.

To all whom it may concern:

Be it known that I, SIMON B. HESS, a citizen of the United States, residing at Jamaica, in the county of Queens and State 5 of New York, have invented certain new and useful Improvements in Electric Signaling Systems, of which the following is a specification.

The system disclosed by this invention is 10 particularly adapted for utilization as an alarm system for protecting, say, from fire, localized territory, factory buildings and the like.

Systems of this class are designed primarily to provide means for sounding an 15 alarm or a plurality of alarms upon the occurrence of a predetermined circumstance; for example, an alarm or a plurality of alarms, of fire, sent from any one of a plurality of stations and giving warning signals 20 at one desired point or at a plurality of desired points in a building or the like, so as to warn the occupants of the existence of a fire to the end that they may make escape, 25 or for the purpose of training the occupants of the building as to the most expeditious means of making their exit in case of fire or other catastrophe, or for the purpose of calling a fire brigade to quarters, &c.

30 In locations where suitable direct current electric service is available, energy for the operation of the alarm system may be obtained therefrom, the energy for the operation of the trouble bell being obtained from a battery.

In locations where the electric service furnishes alternating current, or where there is no available service, current for the operation of the alarm system as well as the 40 trouble bell may be obtained from suitable primary or secondary batteries.

In locations where a suitable and reliable three-wire direct current service is available, energy for the operation of the alarm system may be obtained from one side of the three-wire system, while energy for the operation of the trouble bell may be obtained from the other side of the same system.

50 It is a primary object of this invention to provide a system of the class described, in which a single electromagnetic device is employed to supervise the circuit, to produce a variety of dissimilar trouble signals upon 55 the occurrence of a fault or faults in the circuit, and to transmit an alarm or plu-

rality of alarms upon the operation of a signal transmitting device.

It is another object of this invention to provide a system in which there will be included means for producing upon a single signal receiving device characteristically dissimilar signals, to indicate various different faults as they occur, such for example as a break or ground in the station loop, a ground 65 in the bell loop, or a break in the bell loop.

It is a further object of this invention to provide a signaling system including a large 70 number of signal receiving and signal transmitting devices, supervised in a series circuit, so arranged, that upon the opening of the station loop or the operation of a transmitting device, the receiving devices will become connected directly to the source of current supply, and, upon the closing of the 75 circuit, the transmitting devices will be momentarily connected directly to said source of current supply in series with an electromagnetic device and immediately thereafter in series with the signal receiving 80 devices, all to the end that the system may be effectively operated by a single electromagnetic device.

It is a further object of this invention to provide a resistance so located in the system, 85 that upon the occurrence of a ground upon the bell loop, this resistance will be interposed between the point of contact and the source of energy so as to protect the equipment from the harmful effect of high 90 E. M. F.

It is a further object of this invention to provide a system with a resistance, so located as to be adapted to be included in the circuit upon the reclosing of the station loop, 95 thereby cutting down the current in the station loop, so that, upon the re-opening of the circuit at the transmitting device, sparking at the point of current interruption will be effectively avoided.

100 It is an object of this invention to provide a system wherein there is eliminated the probability of destruction or harmful effect to the signaling apparatus upon the occurrence of an accidental break or ground.

105 It is an important object of this invention to provide a system that may be supervised by means of a current considerably less than is required for the normal operation of the supervising electromagnetic device.

110 It is another object of this invention to provide a system wherein a relatively high E.

M. F. may be employed without sparking at points of current interruption.

Objects and aims of this invention more or less broad than those stated above, together with their inherent advantages, will be in part obvious and in part specifically referred to in the course of the following description of the elements, combinations of means, arrangements of parts, and applications of principles constituting this invention, and the scope of protection contemplated will appear from the claims. I attain these objects and aims in the present embodiment by means of the circuits, devices, apparatus, resistances and sources of current supply illustrated in the accompanying drawings, which are to be taken as a part of these specifications, and constitute a diagrammatic disclosure of the said embodiment.

In the accompanying drawings, Figure 1 shows an application of this invention to a system in which energy for the operation of the alarm as well as the trouble bell is obtained from primary batteries; Fig. 2 shows a modification of a portion of Fig. 1; Fig. 3 shows an application of this invention to a system in which energy for the operation of the alarm is obtained from a direct current electric service, energy for the operation of the trouble bell being obtained from a battery; Fig. 4 shows a modification of a portion of Fig. 3; and Fig. 5 shows an application of this invention to a system in which energy for the operation of the alarm is obtained from one side of a three-wire system and energy for the operation of the trouble bell is obtained from the other side of the same system.

Referring to Fig. 1, 11 is a battery, one terminal of which is connected to junction 12, and the other terminal of which is connected through fuse 13 to junction 14. 32 is an electromagnet, the armature of which is arranged to so manipulate contact levers 23 and 25 that when the armature is in attracted position contact lever 23 touches contact point 22, the other contacts being open, and when the armature is in retracted position point 22 (conductor 39) touches point 21, lever 23 touches point 24, and lever 25 touches point 26. A trouble bell 27 is arranged to be operated by trouble battery 28 when lever 25 touches point 26. A is an ammeter to indicate the flow of current in the normally closed circuit. A signaling station is diagrammatically represented by the break wheel 36 arranged to operate the signaling levers 34, 35. Other similar stations are indicated by the rectangles 38, 38, 38. 40 represents a single stroke bell.

Under normal conditions magnet 32 is energized to attract its armature, the following closed circuit being established:—

65 from lower terminal of battery 11 through

fuse 13, junction 14, conductor 19 of the bell loop, the bells 40 in parallel, conductor 29 of the bell loop, lever 23, point 22, conductor 39 of the station loop, stations 38, signaling levers 35 and 34, conductor 33 of the station loop, magnet 32, conductor 31, ammeter A, conductor 30, conductor 18, junction 12, to upper terminal of battery 11. The winding of magnet 32 is so related to that of the magnets of the bells 40 that the current passing through the circuit just described is sufficient to cause magnet 32 to effectively attract its armature while the bell magnets are unable even to retain their armatures in attracted position.

Upon the pulling of any station and the movement of its breakwheel 36 to operate its signaling levers 34 and 35 and the consequent breaking of the normal closed circuit, magnet 32 will release its armature to move contact levers 23 and 25 to establish the following three circuits:—(1) from junction 14, through conductor 19, the bells 40 in parallel, conductor 29, lever 23, point 24, to conductor 18; (2) from junction 14, through conductor 20, point 21, conductor 39, stations 38, conductor 37, to signaling lever 35 of the operated station, to signaling lever 34 thereat (now open here), conductor 33, magnet 32, conductor 31, ammeter A, conductor 30, to conductor 18; (3) from right hand terminal of trouble battery 28, to trouble bell 27, point 26, lever 25, to left hand terminal of battery 28.

It will be seen that in circuit (1) the bell loop is now connected to the terminals of the battery 11 with no intervening resistance except that of the line conductors. The bell magnets are so constructed and arranged that their armatures are now effectively attracted to sound a stroke of the signal. The closing of circuit (3) causes the ringing of the trouble bell, which continues as long as the armature of magnet 32 remains in its retracted position. When circuit (2) is closed by signaling levers 34 and 35, magnet 32 attracts its armature and reestablishes the normal closed circuit. Upon further movement of breakwheel 36 this operation will be repeated, every interruption of the circuit at the signaling levers 34 and 35 causing the sounding of a stroke of the alarm upon the bells 40.

In case of a break in the station loop magnet 32 will be deenergized, causing a single stroke upon the bells 40 and continuous ringing of the trouble bell 27. In the case of a break in the bell loop, magnet 32 will be deenergized as before, causing the ringing of the trouble bell 27, but as the magnet 32 will be reenergized upon the closing of circuit (2) from conductor 20 to conductor 39, its armature will move to attracted position, resulting in an interrupted ringing of the trouble bell.

Junction 12 may be connected by means of conductor 15 and switch 16 to ground 17. If, while switch 16 is closed, a ground occurs upon conductor 19 of the bell loop magnet 32 will be shunted, causing continuous ringing of the trouble bell 27. In case of a ground on conductor 29 of the bell loop a stroke will be sounded upon the bells 40 and magnet 32 will be shunted as before, causing the ringing of the trouble bell, but as the magnet will be reenergized upon the closing of circuit (2) from conductor 20 to conductor 39, its armature will move to attracted position, resulting in interrupted ringing of the trouble bell. In case of a ground on any part of the station loop magnet 32 will be shunted as before, causing a single stroke upon the bells 40 and continuous ringing of the trouble bell 27. In case there is a small amount of resistance in the circuit through the accidental ground, the fuse 13 will operate to protect the battery from exhaustion. When the ringing of the trouble bell is responded to, the switch 16 may be opened and the fuse replaced, thus putting the alarm system into operative condition, and the ground on the system may then be located and removed.

As magnet 32 will naturally fail more slowly when its circuit is shunted by a ground than when its circuit is opened by a break, the difference in the frequency of the interrupted ringing of the trouble bell provides a means of differentiating between a ground and a break.

Fig. 2 shows another method for connecting the bell loop of Fig. 1, the conductors 19^a and 29^a being substituted for the conductors 19 and 29, respectively, of Fig. 1, and the bells (represented by the reference characters 40^a, 40^b) being connected in series. In Fig. 2, as in Fig. 1, the bell magnet armatures will not be moved to, or retained in, attracted position by the current passing through the normal closed circuit, but when the bell loop is connected directly to the battery upon the opening of the circuit at a station and the consequent retraction of the armature of magnet 32, the bell magnet armatures will be moved to attracted position. In Fig. 2, upon the movement of the armature of magnet 32 to attracted position when the circuit is closed at a station the stroke of the alarm will be sounded. While as shown, bell 40^a is a direct acting tapper, it is evident that an electromechanical gong or other device arranged to sound upon the retraction of its armature could be substituted therefor. In case of a break in the station loop magnet 32 will be deenergized, causing continuous ringing of the trouble bell 27, but no stroke upon the bells 40^a. Operation in the case of a break in the bell loop is the same as in Fig. 1.

Operation in case of a ground upon the bell loop depends upon the location of the ground with reference to the bells 40^a. In any case magnet 32 will be shunted, causing the ringing of the trouble bell. If there is sufficient resistance in the ground path, magnet 32 will be reenergized upon the closing of circuit (2) from conductor 20 to conductor 39, and its armature will move to attracted position, resulting in interrupted ringing of the trouble bell. In case of a ground on any part of the station loop magnet 32 will be shunted, causing continuous ringing of the trouble bell.

Referring to Fig. 3, E represents an electric generator connected to the mains 45 and 46, main 46 being grounded at 17. The armature of electromagnet 32 is arranged to so manipulate contact levers 47, 23 and 25 that when the armature is in attracted position contact point 48 touches contact point 22 (conductor 39), the other contacts being open, and when the armature is in retracted position lever 47 touches point 22, lever 23 touches point 24, and lever 25 touches point 26.

Under normal conditions magnet 32 is energized to attract its armature, the following closed circuit being established:—from main 45 through fuse 13, junction 14, conductor 19 of the bell loop, the bells 40 in series, conductor 29 of the bell loop, junction 43, resistance 42, point 48, conductor 39 of the station loop, stations 38, signaling levers 35 and 34, conductor 33 of the station loop, magnet 32, conductor 31, conductor 18, fuse 13^a, to main 46. The winding of magnet 32 is so related to that of the magnets of the bells 40 that the current passing through the circuit just described is sufficient to cause magnet 32 to effectively attract its armature while the bell magnets are unable even to retain their armatures in attracted position. While magnet 32 is itself a comparatively high resistance magnet, resistance 42 in series therewith assists in securing a minimum value for the normal current flow after the armature of magnet 32 has been moved to attracted position.

Upon the pulling of any station, contact levers 47, 23, and 25 move to establish the following three circuits:—(1) from junction 14, through conductor 19, the bells 40 in series, conductor 29, junction 43, conductor 44, lever 23, point 24, to conductor 18; (2) from junction 14, through conductor 20, resistance 41 therein, lever 47, point 22, conductor 39, stations 38, conductor 37, to signaling lever 35 of the operated station, signaling lever 34 thereat (now open here), conductor 33, magnet 32, conductor 31, to conductor 18; (3) the circuit of trouble bell 27, as in Fig. 1.

It will be seen that circuit (1) connects 130

the bell loop directly to the terminals of the source of energy, as in Fig. 1. The bell magnets are so constructed and arranged that their armatures are now effectively attracted to sound a stroke of the signal. As shown, the bell magnets are connected in series. If bells of a standard resistance and intended for a standard current strength are used, it is evident that the number of them which should be connected in any bell loop depends upon the voltage of the supply circuit. If the number of bells required for any particular installation is not as great as the number corresponding to the supply voltage available a balancing resistance may be inserted in either or both conductors 19 and 29 of the bell loop. When circuit (2) is closed by signaling levers 34 and 35, magnet 32 attracts its armature and reestablishes the normal closed circuit. It will be noticed that resistance 41 is included in circuit (2). This resistance may be made approximately equal to resistance 42, or if desired, may be omitted, thus permitting the flow of an increased amount of current through magnet 32 when its armature is retracted and its magnetic reluctance is greatest.

Operation in case of a break is the same as in Fig. 1.

Operation in case of a ground upon the bell loop depends upon the location of the ground with reference to the bells 40. A stroke will be sounded upon all bells located in the bell loop between junction 14 and the accidental ground, and magnet 32 will be shunted, thus causing the ringing of the trouble bell. If there is sufficient resistance in the ground path, magnet 32 will be reenergized upon the closing of circuit (2) from conductor 20 to conductor 39, and its armature will move to attracted position, resulting in interrupted ringing of the trouble bell. If the ground circuit is of low enough resistance, fuse 13 will operate to disconnect the system. As the ground 17 is a permanent connection, the accidental ground must be removed before the system can be permanently restored to operative condition. Operation in case of a ground on any part of the station loop is the same as in Fig. 1.

Referring to Fig. 4, the armature of electromagnet 32 is arranged to so manipulate contact levers 50, 52, 23, and 25 that when the armature is in attracted position contact lever 50 touches contact point 49, the other contacts being open, and when the armature is in retracted position, lever 50 touches point 51, lever 52 touches point 53, lever 23 touches point 24, and lever 25 touches point 26.

Under normal conditions magnet 32 is energized to attract its armature, the following closed circuit being established:—from

main 45 through fuse 13, junction 14, resistance 42, conductor 19 of the bell loop, the bells 40 in series, conductor 29 of the bell loop, point 49, lever 50, conductor 39 of the station loop, stations 38, signaling levers 35 and 34, conductor 33 of the station loop, magnet 32, conductor 31, conductor 18, fuse 13^a, to main 46. The winding of magnet 32 is so related to that of the magnets of the bells 40 that the current passing through the circuit just described is sufficient to cause magnet 32 to effectively attract its armature while the bell magnets are unable even to retain their armatures in attracted position. While magnet 32 is itself a comparatively high resistance magnet, resistance 42 in series therewith assists in securing a minimum value for the normal current flow after the armature of magnet 32 has been moved to attracted position.

Upon the pulling of any station, contact levers 50, 52, 23, and 25 move to establish the following three circuits:—(1) from junction 14, through lever 52, contact 53, conductor 19, the bells 40 in series, conductor 29, lever 23, point 24, to conductor 18; (2) from junction 14, through conductor 20, resistance 41 therein, point 51, lever 50, conductor 39, stations 38, conductor 37, to signaling lever 35 of the operated station, 95 signaling lever 34 thereat (now open here), conductor 33, magnet 32, conductor 31, to conductor 18; (3) the circuit of trouble bell 27, as in Fig. 1.

It will be seen that circuit (1) connects the bell loop directly to the terminals of the source of energy, as in Fig. 1, the circuit being so arranged however, that contact levers 52 and 23 control what amounts to a "double break" in the ringing current.

The bell magnets are so constructed and arranged that their armatures are now effectively attracted to sound a stroke of the signal.

Operation in case of a break is the same as in Fig. 1.

Operation in case of a ground upon the bell loop depends upon the location of the ground with reference to the bells 40. In any case magnet 32 will be shunted, causing the ringing of the trouble bell, and the sounding of a stroke upon all bells located in the bell loop between junction 14 and the accidental ground. If there is sufficient resistance in the ground path, magnet 32 will be reenergized upon the closing of circuit (2) from conductor 20 to conductor 39, and its armature will move to attracted position, resulting in interrupted ringing of the trouble bell and a succession of strokes upon the alarm bells located between junction 14 and the accidental ground. In case of a ground on any part of the station loop magnet 32 will be shunted as before, causing a stroke to be sounded upon the bells 130

40 and continuous ringing of the trouble bell.

It will be seen that, as the result of the occurrence of a ground on the bell loop, the shunting of resistance 42 in series with the ground will not be continuous, but will be intermittent. Hence for a considerable portion of the time the current through the ground circuit will be very slight and the 10 gongs located in the ground path will be only momentarily subjected to heavy current.

Referring to Fig. 5, E represents an electric generator connected to the mains 45 and 15 46, and E' represents an electric generator connected to the mains 46 and 45^a, main 46 being grounded at 17. The mains 45, 46 and 20 45^a are intended to indicate the three feed wires of any typical "three-wire" direct current system. The armature of electromagnet 32 is arranged to so manipulate contact levers 50, 52, 23 and 25 that when the armature is in attracted position contact lever 50 touches contact point 49, the other contacts 25 being open, and when the armature is in retracted position, lever 50 touches point 51, lever 52 touches points 53 and 54, lever 23 touches point 24, and lever 25 touches point 26.

30 Under normal conditions magnet 32 is energized to attract its armature, the following closed circuit being established:—from main 45 through fuse 13, junction 14, resistance 42, conductor 19 of the first bell loop, the bells 40 in series therein, conductor 29^b of the second bell loop, the bells 40 in series therein, point 49, lever 50, conductor 39 of the station loop, stations 38, signaling levers 35 and 34, conductor 33 of the station loop, 40 magnet 32, conductor 31, conductor 18, fuse 13^a to main 46. The winding of magnet 32 is so related to that of the magnets of the bells 40 that the current passing through the circuit just described is sufficient to cause 45 magnet 32 to effectively attract its armature while the bell magnets are unable even to retain their armatures in attracted position. While magnet 32 is itself a comparatively high resistance magnet, resistance 42 in 50 series therewith assists in securing a minimum value for the normal current flow after the armature of magnet 32 has been moved to attracted position.

Upon the pulling of any station, contact 55 levers 50, 52, 23, and 25 move to establish the following four circuits:—(1) from junction 14, through lever 52, contact 53, conductor 19, the bells 40 in the first bell loop in series, conductor 29, lever 23, point 24, 60 to conductor 18; (1^a) from junction 14, through lever 52, contact 54, conductor 29^b, the bells 40 in the second bell loop in series, conductor 29, lever 23, point 24, to conductor 18; (2) from junction 14, through 65 conductor 20, resistance 41 therein, point 51,

lever 50, conductor 39, stations 38, conductor 37, to signaling lever 35 of the operated station, signaling lever 34 thereat (now open here), conductor 33, magnet 32, conductor 31, to conductor 18; (3) from main 45^a, 70 through fuse 13^b, resistance 55, trouble bell 27, point 26, lever 25, to main 46.

It will be seen that circuits (1) and (1^a) connect the bell loops directly to the terminals of the source of energy E, contact 75 levers 52 and 23 controlling the "double break" as in Fig. 4. If the bells 40 are of the type used in Figs. 3 and 4, it is evident that twice as many may be controlled from the one magnet 32. The two bell loops may remain separated all the way back to the lever 23, instead of being connected jointly by the conductor 29, as shown. When this is done all of the exposed wiring will be 80 "under test."

It will also be seen that circuit (3) connects the trouble bell 27 in series with resistance 55 to the terminals of the source of energy E'. The resistance 55 may be used, as shown, to decrease the current through 90 the trouble bell 27, or a high resistance trouble bell may be used if desired. By connecting the trouble circuit and the alarm circuit to the mains in the manner shown, so that the blowing of the fuses in either 95 circuit will not affect the operation of the other circuit, a local battery for the trouble bell may be dispensed with.

In case of a break in the station loop magnet 32 will be deenergized, causing a 100 single stroke upon the bells 40 and continuous ringing of the trouble bell 27. In case of a break in either bell loop, magnet 32 will be deenergized as before, causing the ringing of the trouble bell and the sounding of 105 a stroke upon all bells 40 in the unbroken loop, but as the magnet 32 will be deenergized upon the closing of circuit (2) from conductor 20 to conductor 39, its armature will move to attracted position, resulting in 110 interrupted ringing of the trouble bell and a succession of strokes upon the alarm bells in the unbroken loop.

Operation in case of a ground upon either bell loop depends upon the location of the 115 ground with reference to the bells 40 in the grounded loop. In any case magnet 32 will be shunted, causing the ringing of the trouble bell, and the sounding of a stroke upon all bells in the nongrounded loop and 120 upon all bells located in the grounded loop between junction 14 and the accidental ground. If there is sufficient resistance in the ground path, magnet 32 will be reenergized upon the closing of circuit (2) from 125 conductor 20 to conductor 39, and its armature will move to attracted position, resulting in interrupted ringing of the trouble bell and a succession of strokes upon all alarm bells in the nongrounded loop and the 130

alarm bells located in the grounded loop between junction 14 and the accidental ground. In case of a ground on any part of the station loop magnet 32 will be shunted as before, causing a stroke to be sounded upon the bells 40 in both bell loops and continuous ringing of the trouble bell.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, might be said to fall therebetween.

What I claim and desire to secure by Letters Patent of the United States is:—

1. An electric signaling system comprising a source of energy, a bell loop, a resistance, a station loop, an electromagnet therein, and means controlled by said magnet upon energization thereof for connecting said loops and said resistance in series with each other and to the source of energy and upon deenergization thereof for short-circuiting said resistance and for connecting said loops in parallel with each other and to the source of energy.

2. An electric signaling system comprising a source of energy, a bell loop, a resistance, a station loop, an electromagnet therein, a trouble signal, and means controlled by said magnet upon energization thereof for connecting said loops and said resistance in series with each other and to the source of energy and upon deenergization thereof for short-circuiting said resistance and for connecting said loops in parallel with each other and to the source of energy and actuating said trouble signal.

3. An electric signaling system comprising a source of energy, a bell loop, a resistance, a station loop, an electromagnet therein, a trouble signal, and means controlled by said magnet upon energization thereof for connecting said loops and said resistance in series with each other and to the source of energy and upon deenergization thereof for short-circuiting said resistance, connecting said trouble signal to the source of energy, and for connecting said loops in parallel with each other and to the source of energy.

4. An electric signaling system comprising a source of energy, two bell loops, a resistance, a station loop, an electromagnet therein, and means controlled by said magnet upon energization thereof for connect-

ing said loops and said resistance in series with each other and to the source of energy and upon deenergization thereof for short-circuiting said resistance and for connecting said loops in parallel with each other and to the source of energy.

5. An electric signaling system comprising a source of energy, two bell loops, a resistance, a station loop, an electromagnet therein, a trouble signal, and means controlled by said magnet upon energization thereof for connecting said loops and said resistance in series with each other and to the source of energy and upon deenergization thereof for short-circuiting said resistance and for connecting said loops in parallel with each other and to the source of energy and actuating said trouble signal.

6. An electric signaling system comprising a source of energy, two bell loops, a resistance, a station loop, an electromagnet therein, a trouble signal and means controlled by said magnet upon energization thereof for connecting said loops and said resistance in series with each other and to the source of energy and upon deenergization thereof for short-circuiting said resistance, connecting said trouble signal to the source of energy, and for connecting said loops in parallel with each other and to the source of energy.

7. An electric signaling system comprising a source of energy, a bell loop, a station loop, an electromagnet therein, an open shunt across said bell loop, and means controlled by said electromagnet upon deenergization thereof for connecting said shunt and said station loop in series with each other and to the source of energy.

8. An electric signaling system comprising a source of energy, a bell loop, a resistance, a station loop, an electromagnet therein, a trouble signal, and means controlled by said magnet upon energization thereof for connecting said loops and said resistance in series with each other and to the source of energy and upon the occurrence of a break in the station loop or a break in the bell loop for actuating said trouble signal to produce different trouble indications and upon deenergization of said magnet for short-circuiting said resistance and for connecting said loops in parallel with each other and to the source of energy and actuating said trouble signal.

9. An electric signaling system comprising a source of energy, a bell loop, a resistance, a station loop, an electromagnet therein, a trouble signal, and means controlled by said magnet upon energization thereof for connecting said loops and said resistance in series with each other and to the source of energy and upon the occurrence of a break in the station loop or a break in the bell loop for actuating said trouble signal.

to produce different trouble indications and upon deenergization of said magnet for short-circuiting said resistance, connecting said trouble signal to the source of energy, 5 and for connecting said loops in parallel with each other and to the source of energy.

10. An electric signaling system comprising a source of energy, two bell loops, a resistance, a station loop, an electromagnet 10 therein, a trouble signal, and means controlled by said magnet upon energization thereof for connecting said loops and said resistance in series with each other and to the source of energy and upon the occurrence 15 of a break in the station loop or a break in the bell loop for actuating said trouble signal to produce different trouble indications and upon deenergization of said magnet for short-circuiting said resistance and 20 for connecting said loops in parallel with each other and to the source of energy and actuating said trouble signal.

11. An electric signaling system comprising a source of energy, two bell loops, a resistance, a station loop, an electromagnet 25 therein, a trouble signal, and means controlled by said magnet upon energization thereof for connecting said loops and said resistance in series with each other and to 30 the source of energy and upon the occurrence of a break in the station loop or a break in the bell loop for actuating said trouble signal to produce different trouble indications and upon deenergization of said magnet for short-circuiting said resistance, connecting 35 said trouble signal to the source of energy, and for connecting said loops in parallel with each other and to the source of energy.

12. An electric signaling system comprising a source of energy, a bell loop, a station loop, an electromagnet therein, an open shunt across said bell loop, a resistance in said open shunt, and means controlled by said electromagnet upon deenergization 45 thereof for connecting said shunt and said station loop in series with each other and to the source of energy.

13. An electric system comprising a bell loop, a station loop, a normally grounded 50 source of energy therefor, an electromagnet connected at one end of said station loop adjacent to the grounded terminal of the source of energy, and means controlled by said magnet for connecting the other end 55 of said station loop to the non-grounded terminal of said source of energy through a resistance.

14. An electric signaling system comprising a normally grounded source of energy, 60 a bell loop, a resistance, a station loop, an electromagnet therein, a trouble signal, and means controlled by said magnet for connecting said loops and said resistance in series with each other and to the source of 65 energy and upon the occurrence of a break or a ground in the station loop, a ground in the bell loop or a break in the bell loop for actuating said trouble signal to produce different trouble indications and upon deenergization 70 of said magnet for short-circuiting said resistance and for connecting said loops in parallel with each other and to the source of energy and actuating said trouble signal.

Signed at New York, in the county of 75 New York and State of New York, this 18th day of September, A. D. 1916.

SIMON B. HESS.
